UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,120,726.

Specification of Letters Patent.

Patented Dec. 15, 1914.

Application filed September 11, 1905, Serial No. 277,916. Renewed June 21, 1910. Serial No. 568,169.

To all whom it may concern:

Be it known that I, WILLIAM A. LORENZ, residing at Hartford, in the county of Hartford and State of Connecticut, have invented 5 certain new and useful Improvements in Type-Writing Machines, of which the following is a full, clear, and exact description, such as will enable others skilled in the art to which it appertains to make and use the 10 same.

This invention relates to typewriting machines and the like and, while capable of employment in a variety of relations in machines of other types, it is especially adapted 15 for use in those known as "silent typewriters".

It has for a broad object the provision of mechanism designed to produce a machine which will operate substantially without 20 noise.

Another object is to provide means adapted to arrest the motion of the various moving parts of a typewriting machine in such a manner as to practically eliminate 25 the noise usually incident to such operations.

More especially, the object of my present invention is to produce a stop for the key levers in a typewriting machine of such a nature as to eliminate concussion or impact 30 during the arresting of their movements, thus insuring a silent operation.

Other objects will be in part obvious and in part pointed out hereinafter.

The invention, accordingly, consists in 35 the features of construction, combinations of elements and arrangement of parts which will be exemplified in the mechanism herein- 40 after described and the scope of the application of which will be indicated in the following claims.

In the accompanying drawings, wherein are illustrated several of the various possible embodiments of my invention, Figure 1 is an elevation of the same. Fig. 2 is a 45 similar view showing the parts in a different position. Fig. 3 is an elevation of another embodiment of the same. Fig. 4 is a similar view of the mechanism illustrated in Fig. 3 showing the parts in a different 50 position. Fig. 5 is an elevation of another embodiment of the same. Fig. 6 is a similar

view of the mechanism illustrated in Fig. 5 showing the parts in a different position. Fig. 7 is an elevation of still another embodiment of the same. Fig. 8 is a similar 55 view of the mechanism illustrated in Fig. 7 showing the parts in a different position.

Similar reference characters refer to similar parts throughout the several views of the drawings.

Preliminary to a description of the more specific features of my invention and in order that the general objects thereof may be more easily understood, it may be here noted that in the production of a typewriting machine which will operate in all respects without noise, it is essential to provide suitable mechanism adapted silently to arrest the motion of the several movable parts of the machine. As tending toward that end, 70 therefore, I have found it desirable to provide means adapted to arrest the movements of the key levers without impact or concussion, thereby insuring a substantially silent operation. The above and other advantages 75 are secured in constructions of the nature of that hereinafter described.

Referring now to the drawings and particularly Figs. 1 and 2, there is shown at 1 a key lever suitably journaled upon rod 2 80 positioned in the frame of the machine, which key lever is maintained in its upward position against a cushioned stop 3 by means of spring 4 connected to the key lever 1 at 5 and to a fixed part of the machine. Key 85 lever 1 is provided at its lower extremity with a curved portion 6 preferably cut away, as at 7, the purpose of which will be apparent hereinafter, and to said curved portion 6 the end 8 of a flat spring 9 is attached, as 90 by means 10, the opposite end thereof having a pivotal connection at 11 with an oscillating arm 12 pivoted in turn to a fixed portion of the machine at 13.

In the operation of the above described 95 embodiment which should be largely obvious, it will be understood that during the stroke of the key lever from its normal position, as shown in Fig. 1, to the position shown in Fig. 2, spring 9 is gradually 100 brought into contact or progressively engaged with the curved portion 6, oscillating

arm 12 serving to carry the end of spring 9 toward its point of fastening by reason of the lessening of the distance between the ends of spring 9, due to its assuming a 5 curved form.

The embodiment shown in Figs. 3 and 4 differs slightly from that above described in that spring 9 rests upon a fixed pin or support 14, the operation being substantially 10 the same as that above described, spring 9 sliding slightly along the surface of said pin or support 14 during its downward stroke.

Referring now to Figs. 5 and 6, I have, 15 in this instance, bent the end of spring 9 as at 15 and provided a stop 16 fixed to the frame of the machine, in which is provided a slight depression 17, adapted to receive and support the free end of spring 9. During 20 the depression of key lever 1, spring 9 bending slightly at 15, as shown in Fig. 6, compensates for the engagement of spring 9 with the curved portion 6.

As shown in Figs. 7 and 8, I have provided a fixed bar or stop 18 having a curved periphery 19 to which is attached by suitable means, as screw 20, a flat spring 21. The key lever 1 is, in this instance, provided with a depending projection 22 adapted 30 to rest upon the free end of spring 21 and during the depression of key lever 1, spring 21 will be brought gradually into contact or progressively engaged with the curved periphery 19 of fixed stop 18, the 35 movement thereof being arrested when the position shown in Fig. 8 is reached.

It will be noted that in each of the embodiments illustrated in Figs. 1 to 6 inclusive, I have so constructed the curved portion 40 with which spring 9 is adapted to be progressively engaged or bent about that the portion of said spring in engagement with the stop will fall without the end of said curved portion. By this arrangement, 45 a slight elasticity is given the key lever 1, by reason of the short extent of spring 9 between the end of the cut away portion of curved portion 6 of key lever 1 and the fixed stop. It will be seen that this elasticity or 50 springiness, may be reduced to a minimum by a lessening of the distance between the fixed stop and the end of curved portion, or the same may be eliminated entirely by arranging the fixed stop directly under the 55 outer extremity of curved portion 6.

In Figs. 7 and 8 the results next above described may be effected, as will be apparent, by locating the depending portion 22 of key lever 1 nearer to or directly over 60 the extremity of fixed stop 18.

It will be further noted that by a gradual lessening of the effective length of springs 9 or 21 in the stroke of the key lever to impression a constantly increasing

resistance is afforded during such stroke, 65 thus serving to gradually arrest the movement thereof, and moreover, it will be apparent that in all the embodiments herein shown and described, spring 9 or 21 assist in the returning of the key levers to their normal position under the influence of springs 4. 70

It will, accordingly, appear that I have provided mechanism well adapted to attain the several objects of my invention and which is, moreover, characterized by simplicity of structure and efficiency of action, as the stroke of the key levers is yieldingly 75 and yet positively arrested without impact or concussion and the production of noise is thereby prevented. 80

While I have shown my invention as applied to key levers, it should be obvious that it is well adapted to be applied to other moving parts of a typewriting machine, and I do not wish to be understood as limiting 85 myself to such employment, nor even to its use in machines of the type described, as many of the features are capable of use in similar relations in machines of other types, although of peculiar value in the relation 90 shown.

Having described my invention, what I claim as new and desire to secure by Letters Patent is:—

1. In a typewriting machine, in combination, a movable member, a fixed stop, and a resilient body interposed therebetween, said resilient body being so arranged with respect to said movable member and said fixed stop as to have its surface progressively engaged with the surface of one of the same during a movement of said movable member toward said fixed stop. 95

2. In a typewriting machine, in combination, a movable member, means adapted to return said member to normal position, a fixed stop, and a resilient body so arranged with respect to said movable member and said fixed stop as to have its surface gradually brought into contact with one of the same during a movement of said movable member toward said fixed stop. 100

3. In a typewriting machine, in combination, a movable member, resilient means adapted to return said member to normal position, a fixed stop, and a resilient body interposed between said movable member and said stop, the arrangement of said resilient body with respect to said movable member and said fixed stop being such that 115 during a movement of the former in the direction of the latter, the effective length of said resilient body will be gradually reduced.

4. In a typewriting machine, in combination, a movable member, a fixed member, and a flat resilient body interposed therebetween, said resilient body being so arranged 120

with respect to said aforementioned members as to be progressively engaged with the surface of one of said members and remain in engagement therewith during a movement of the former member toward the latter member.

5 5. In a typewriting machine, in combination, a movable member, a fixed member, one of said members being provided with a 10 curved surface, and a resilient body interposed between said members, said resilient body being so arranged with respect to said members that during a movement of the former toward the latter said resilient body 15 will have its surface progressively engaged with said curved surface.

6 6. In a typewriting machine, in combination, a movable member, a fixed member, one of said members being provided with a 20 curved surface and a resilient body so arranged with respect to said members that during a movement of the former toward the latter, said resilient body will have its surface brought gradually into contact with 25 said curved surface, thereby reducing the effective length of said resilient body, such operation effecting a constantly increasing resistance to the movement of said first-mentioned member.

30 7. In a typewriting machine, in combination, a movable member, a fixed member, one of said members being provided with a curved surface, and a resilient body attached to one of said members, said resilient body 35 being so arranged with respect to said members that a movement of the former toward the latter will effect a progressive engagement of the surface of said resilient body with said curved surface.

40 8. In a typewriting machine, in combination, a movable member, a fixed member, one of said members being provided with a curved surface, and a resilient body attached to one of said members and having a frictional connection with the other of said members, said resilient body being so arranged with respect to said members that a movement of the former toward the latter will effect a progressive engagement of the 45 surface of said resilient body with said curved surface.

9. In a typewriting machine, in combination, a movable member, a fixed member, one of said members being provided with a 55 curved portion, and a flat resilient body attached to and arranged adjacent said curved portion and adapted during a movement of said first-mentioned member toward said second-mentioned member to be progressively engaged with said curved portion.

60 10. In a typewriting machine, in combination, a movable member, a fixed member, one of said members being provided with a curved portion, and a resilient body of

greater length than said curved portion connected to one of said members, said resilient body being so arranged with respect to said members that a movement of the former toward the latter will effect a progressive engagement of said resilient body with said 65 curved portion.

11. In a typewriting machine, in combination, a movable member, a fixed member, one of said members being provided with a curved surface, and a resilient body of 70 greater length than said curved surface secured between one of said members and having a frictional connection with the other of said members, the point of frictional connection being without the extremity of said 75 curved surface, said resilient body being adapted when the first mentioned member is moved in the direction of said fixed member to be progressively engaged with said 80 curved surface.

85 12. In a typewriting machine, in combination, a movable member, a fixed member, one of said members having a curved surface, and a flat spring interposed therebetween, said spring being so arranged with respect to said movable member and said fixed member as to be progressively engaged with the curved surface of one of the same during a movement of said movable member toward said fixed member.

90 13. In a typewriting machine, in combination, a movable member, spring means adapted to return said member to normal position, a fixed stop, and a flat spring interposed therabetween and so arranged as to 100 be gradually brought into contact with one of the same during a movement of said movable member toward said fixed stop.

105 14. In a typewriting machine, in combination, a movable member, a fixed member, one of said members being provided with a curved portion, and a flat spring interposed between said members, said flat spring being so arranged with respect to said members that during a movement of the former 110 toward the latter said flat spring will be progressively engaged with said curved portion.

115 15. In a typewriting machine, in combination, a movable member, a fixed member, one of said members being provided with a curved surface, a flat spring so arranged with respect to said members that during a movement of the former toward the latter said flat spring will be brought gradually 120 into contact with said curved surface, thereby reducing its effective length, said operation effecting a constantly increasing resistance to the movement of said first-mentioned member.

125 16. In a typewriting machine, in combination, a movable member, a fixed member, one of said members being provided with a

1 curved surface, and a flat spring secured to one of said members and having a frictional connection with the other of said members and so arranged with respect to said members that a movement of the former toward the latter will effect a progressive engagement of said flat spring about one of said members.

17. In a typewriting machine in combination, a movable member, a fixed member, one of said members being provided with a curved portion, and a flat spring of greater length than said curved portion attached to one of said members and having a frictional connection with the other of said members and so arranged with respect to said members that a movement of the former toward the latter will effect a progressive engagement of said spring about one of said members.

18. In a typewriting machine in combination, a movable member, a fixed member, one of said members being provided with a curved portion, and a flat spring of greater length than said curved portion attached to one of said members and having a frictional connection with the other of said members, the point of frictional connection being without the extremity of said curved portion, said spring being so arranged with respect to said members that a movement of the former toward the latter will effect a progressive engagement of said spring about said curved portion.

19. In a typewriting machine, in combination, a key lever, a fixed stop therefor, one of said parts being provided with a curved surface, and a flat spring fastened to one of said parts and engaging the other thereof adapted to be progressively engaged with said curved surface during a movement of the key lever toward said stop.

20. In a typewriting machine, in combination, a movable part, a return spring therefor, and means for silently arresting the movement of said part comprising a fixed part and a resilient body attached to one of said parts, said resilient body being so constructed with respect to said parts that the movement of the former toward the latter will effect a progressive engagement of said resilient body with one of said parts.

21. In a typewriting machine, in combination, a movable part and a fixed part, one of said parts having a curved surface and a flat spring secured at one end to one of said parts adapted progressively to engage said curved surface as said movable part approaches said fixed part.

22. In a typewriting machine, in combination, a movable part, a finger key adapted to be operated upon to actuate said movable part, and a fixed part, one of said parts having a curved surface, and a flat spring

secured at one end to one of said parts adapted progressively to engage said curved surface as said movable part approaches said fixed part when said finger key moves.

23. In a typewriting machine, in combination, a finger key, a member having a curved surface adapted to be moved as said key moves, and a flat spring operatively connected to a relatively fixed part of the machine and with said member adapted progressively to engage said curved surface when said member approaches the point of connection between said spring and the machine.

24. In a typewriting machine, in combination, a manually operating member through which the type are actuated, said member being provided with a curved surface, a flexible member having one end secured adjacent said curved surface and the other end portion operatively connected with the frame of the machine and spaced from said operating member, whereby said flexible member is alternately rolled upon and unrolled from said curved surface as the corresponding operating member is actuated.

25. In a typewriting machine, in combination, a manually operating member through which the type are actuated said member being provided with a curved surface, resilient means having one end secured adjacent said curved surface and the other end portion operatively connected with the frame of the machine and spaced from said operating member, whereby said resilient means is alternately rolled upon and unrolled from said curved surface as the corresponding operating member is actuated.

26. In a typewriting machine, in combination, a manually operating member through which the type are actuated, said member being provided with a curved surface, a flexible member having one end secured adjacent said curved surface and the other end portion operatively connected with the frame of the machine and spaced from said operating member, whereby said flexible member is alternately rolled upon and unrolled from said curved surface as the corresponding operating member is actuated, and a spring member operatively connected with one of said parts adapted to return said manually operating member to normal position.

27. In a typewriting machine, in combination, a manually operated member through which the type are actuated, said member being provided with a curved surface, a flexible member having one end secured adjacent said curved surface and so positioned as to alternately roll upon and unroll from said curved surface as the corresponding operated member is actuated.

28. In a typewriting machine, in combina-

tion, a manually operated member through which the type are actuated, said member being provided with a curved surface a flexible member having one end secured adjacent to said curved surface and so positioned as to alternately roll upon and unroll from said curved surface as the corresponding operated member is actuated, and spring means

for returning said manually operated member to normal position. 10

In testimony whereof I affix my signature, in the presence of two witnesses.
